UNITED STATES PATENT OFFICE.

FRANCIS P. FOULK, OF INDIANAPOLIS, INDIANA.

MULTIPLE-FILAMENT LAMP.

Application filed October 18, 1920. Serial No. 417,541.

To all whom it may concern:

Be it known that I, FRANCIS P. FOULK, a citizen of the United States, residing at Indianapolis, in the county of Marion and

State of Indiana, have invented new and useful Improvements in Multiple-Filament Lamps, of which the following is a specification.

This invention relates to a multiple filament lamp and has for its primary object the novel manner of arranging the filament and passing current therethrough so that should one or more filaments be destroyed the remaining filaments will continue to glow thereby preventing the lamps from becoming useless.

An object of the invention is the novel manner of arranging the leads, supports, and filaments so that a systematic arrangement can be given to the filaments and light distributed properly thereby greatly increasing the usefulness of the lamp.

With these and other objects in view the invention will be better understood from the following detailed description taken in connection with the accompanying drawing wherein:

Fig. 1 is a diagrammatic view illustrating the relation of the filaments.

Fig. 2 is a top plan view.

Fig. 3 is a diagrammatic view, showing the method of wiring nitrogen type lamp.

Again referring to the drawing illustrating my invention the numeral 1 designates the usual glass stem of an electric lamp. This stem has passing therethrough, at right angles, two leads 2 and 3, one positive and the other negative. An upper set of sup-

ports 4 is arranged directly below the leads and a lower set of supports 5 is connected to the lower end of the stem. The filaments 6 are connected and supported by the supports in a manner to have zigzag formation and are electrically connected to the leads to provide sections 7, 8, 9, and 10, each receiving current independent of the other section as clearly shown in Fig. 2 so that should one section burn out the remaining sections will continue to glow and this action will continue until each section is burned out thereby materially prolonging the life of the lamp.

In Figure 3, I have illustrated the usual negative current wire "a" and the usual positive current wire "b" connected to the leads 2 and 3 so that they may be electrically connected to any source of supply.

It is, of course, to be understood that any number of leads may be used to provide any number of sections and the filaments may be supported by the stem in other relations, therefore, I do not desire to be limited in any manner except as set forth in the claim hereunto appended.

Having thus described my invention what I claim is:

An incandescent lamp including a supporting stem, supports radiating from the stem, a filament mounted upon the supports, and leads extending from the stem at an angle to each other and disposed alternately between certain of the supports to support and electrically connect the filament in independent groups.

In testimony whereof I affix my signature.
FRANCIS P. FOULK.
